UNITED STATES PATENT OFFICE

150,190

DESIGN FOR AN AIRPLANE

Franklin C. Albright, San Marino, Calif., assignor
to Consolidated Vultee Aircraft Corporation,
San Diego, Calif., a corporation of Delaware

Application May 25, 1946, Serial No. 130,066

Term of patent 3½ years

(Cl. D71—1)

To all whom it may concern:

Be it known that I, Franklin C. Albright, a citizen of the United States, residing at San Marino, in the county of Los Angeles and State of California, have invented a new, original, and ornamental Design for an Airplane, of which the following is a specification, reference being had to the accompanying drawing, forming a part thereof.

In the drawings:

Figure 1 is a top plan view of an airplane, showing my new design;

Figure 2 is a front elevational view;

Figure 3 is a top perspective view;

Figure 4 is a side elevational view.

I claim:

The ornamental design for an airplane, substantially as shown.

FRANKLIN C. ALBRIGHT.
